UNITED STATES PATENT OFFICE.

EMERSON L. CLARK, OF LAKEWOOD, OHIO, ASSIGNOR, BY MESNE ASSIGNMENTS, TO NATIONAL CARBON COMPANY, INC., A CORPORATION OF NEW YORK.

PYROMETER.

1,312,951.

Specification of Letters Patent.

Patented Aug. 12, 1919.

Original application filed December 19, 1912, Serial No. 737,640. Divided and this application filed July 23, 1913. Serial No. 780,636.

To all whom it may concern:

Be it known that I, EMERSON L. CLARK, a citizen of the United States, residing at Lakewood, in the county of Cuyahoga and 5 State of Ohio, have invented a certain new and useful Improvement in Pyrometers, of which the following is a full, clear, and exact description.

My invention relates to pyrometer systems and provides means for correcting inaccuracies due to change in temperature of cold junctions in the thermopile, as also described in my application Serial No. 737,640, filed December 19th, 1912, of which 10 15 this application is a division.

In thermopiles the "cold junctions" generate E. M. F.'s, but in a direction opposed to the E. M. F. of the hot junction. The E. M. F. impressed on the galvanometer is 20 therefore less than that of the hot junction. Consequently allowance must be made for the E. M. F. of the cold junctions in using the thermopile to determine temperatures. If the temperature of the "cold junctions" 25 is maintained constant the correction would be a simple matter as the galvanometer would be calibrated for the drop in E. M. F. caused by the counter E. M. F. However, the temperature of the "cold junctions" 30 cannot easily be maintained constant in practice. It is, therefore, necessary to provide means to compensate for such change in the temperature.

The manner in which the compensation is 35 accomplished will be apparent from the following description, reference being had to the drawings in which,

Figure 1 is a view of one form of compensating system.

40 Fig. 2 diagrammatically illustrates the circuits of the system shown in Fig. 1.

Referring to Fig. 1, the thermopile here illustrated has a hot junction 1 and cold junctions 2 and 3. The cold junction 3 is 45 connected through a resistance r to one terminal 4 of the galvanometer and the cold junction 2 is directly connected to the other terminal 5. A galvanometer circuit is diagrammatically represented by the resistance r^3 connected to these two terminals. A resistance r^1 having a high positive temperature coefficient has one terminal connected to the cold junction 2 and the other to the binding post 4. This resistance is wound

around, or otherwise arranged in close 55 proximity to the cold junction so that it will be subjected to the same temperature. This resistance, of course, would be properly insulated so that no contacts would be made at other points than those indicated. The resistance r^1 is in effect made adjustable by putting in the circuit another resistance r^6 which may be located near the galvanometer if desired. By changing the resistance r^6 the effect of the resistance 60 r^1 may be varied.

The working of the system shown in Fig. 1 can best be understood by referring to the diagrammatic representation shown in Fig. 2. With the cold junction 2 and 3 70 at a certain temperature, say 24 degrees centigrade, the galvanometer will be calibrated to indicate the true E. M. F. of the hot junction 1. The scale reading, of course, can be calibrated to read directly 75 in degrees, inasmuch as the E. M. F. is proportional to the temperature of the hot junction. However, if the temperature of the hot junction is unchanged and the temperatures of the cold junctions be increased the resultant E. M. F. impressed on the galvanometer would be less were it not for the compensating coil r^1 in shunt to it. Since this coil is subjected to a like increase of temperature its resistance is increased. The increase of resistance in coil 80 r^1 diminishes the current flowing in the main line resistance r and thus diminishes the drop therearound. The decrease in drop compensates for the decrease of voltage 85 in the thermocouple and the voltage impressed on the galvanometer remains constant. The galvanometer reading will therefore be unaffected by the increase in the temperature of the cold junction. 90

The compensation obtained by this arrangement can be made substantially exact only when the temperature of the hot junctions is unchanged. If the resistances are arranged to exactly compensate when 100 the hot junction temperature is, say 900 degrees C. there will be over-compensation when the hot junction is at a temperature of say 1200 degrees C. for a like variation in the cold junction temperature when the 105 hot junction is at a lower temperature, say 600 degrees C. However, this arrangement without any additional modifications more

correctly indicates the temperature of the hot junctions than if the thermocouple had been connected directly to the galvanometer without any compensating arrangement.

- 5 The system can be made to compensate more accurately for various temperatures of the hot junction by altering the resistances r^1 r and r^6 at certain points in the galvanometer reading. The two resistances r^1 10 and r should be adjusted in such a way that they will always maintain substantially the same ratio to each other. That is, the ratio should remain substantially constant as the resistances are adjusted, if 15 the resistance r^1 does not meanwhile change in temperature. This change in r^1 due to temperature changes, of course, changes the ratio. Since the calibration of the galvanometer requires that the equivalent resistance 20 of the circuit be the same, the resistance r^6 also is varied at the same time. In this way the over-compensation and under-compensation may be as small as desired. For a certain rise in the indication 25 of the galvanometer due to increase in temperature of the hot junction, the resistance r^1 and r^6 may be increased and the resistance r decreased a predetermined amount. On a decrease in indication the reverse 30 change may be made. A scale A may be made on the rheostat to show where the pointer B must be moved to adjust for changes in the temperature of the hot junction. The changes may be made as fine as 35 desired. The resistance r^1 may be varied by varying the resistance r^6 in circuit with it.
- The resistances r and r^6 are merely for the 40 purposes of adjustment, as will be obvious from the previous explanation. For a small temperature range of hot junction temperature, the galvanometer will indicate the temperatures substantially correctly without these two adjustable resistances. In the 45 drawing the resistances r and r^6 are shown adjustable so that they can be reduced to zero or increased to any desired amount to make the system properly adjustable for all ranges of hot junction temperature.
- 50 In Fig. 2 the resistance r^6 is not shown as a separate resistance. This figure is a dia- 55 grammatic representation and the resistance r^1 is shown adjustable itself. It will be obvious that adjusting the resistance r^1 pro- 60 duces the same result as adjusting the resistance r^6 . In practice, however, it is much more preferable to have the separate resistance r^6 to adjust the compensating coil circuit, as it is much easier to manipulate, and furthermore the active turns on the com- 65 pensating coil are then the same for all ad- justments.

Having described my invention, what I claim is:

1. In a pyrometer system, a galvanometer, 65 a thermocouple, a resistance connected between the thermocouple and galvanometer and a second resistance with a positive temperature coefficient connected in shunt to the galvanometer, said resistances being proportioned to approximately compensate for temperature variations in the cold junction of said thermocouple for a predetermined temperature at the hot junction.

2. In a pyrometer system, a galvanometer, 75 a thermocouple connected thereto by two leads, an adjustable resistance in one of said leads, and a resistance connected in shunt to the galvanometer responsive to temperature changes of the cold junctions of the thermo- 80 couple.

3. In a pyrometer system, a galvanometer, a thermocouple connected thereto by two leads, an adjustable resistance in one of said leads, a resistance having a positive temperature coefficient of resistance connected in shunt to the galvanometer, said second resistance being located in close proximity to the cold junction of the thermocouple. 85

4. In a pyrometer system, a galvanometer, 90 a thermocouple, a resistance connected between the thermocouple and galvanometer, a second resistance with a positive temperature coefficient connected in shunt to the galvanometer, and means for varying the re- 95 sistance of the circuit containing said second mentioned resistance.

5. In a pyrometer system, a galvanometer, a thermocouple, a resistance connected between the thermocouple and the galvanometer, a second resistance with a positive temperature coefficient connected in shunt to the galvanometer, and means for varying both of said resistances. 100

6. In a pyrometer system, a galvanometer 105 having a resistance, a thermocouple, a sec- 110 ond resistance connected between the ther- mocouple and the galvanometer, a third re- sistance with a positive temperature coeffi- 115 cient located adjacent the cold junctions of said thermocouple and connected in shunt to the galvanometer, and means for simultane- 120 ously varying all of said resistances.

7. In a pyrometer system, a galvanometer 115 having a resistance, a thermocouple, a sec- 120 ond resistance connected between the ther- mocouple and the galvanometer, a third re- sistance with a positive temperature coeffi- 125 cient located adjacent the cold junctions of said thermocouple and connected in shunt to the galvanometer, and means for simul- taneously increasing the galvanometer re- sistance while decreasing the second and third resistances.

8. In a pyrometer system, a galvanometer, 125 a thermocouple, a resistance connected be- 130 tween the galvanometer and one cold junc- 135 tion of the thermocouple, a compensating

resistance located adjacent the cold junctions of said thermocouple and connected in shunt to the galvanometer, means for adjusting said resistances, and a device operating with said means to indicate the proper adjustment for the temperature of the hot junction.

9. A renewable thermo-electric couple unit comprising shunt and series resistances,

proportioned to correct individual characteristics of the couple.

In testimony whereof, I hereunto affix my signature.
